UNITED STATES PATENT OFFICE.

HORACE H. DAYTON, OF WORCESTER, MASSACHUSETTS.

IMPROVEMENT IN CORSETS.

Specification forming part of Letters Patent No. 39,126, dated July 7, 1863.

To all whom it may concern:

Be it known that I, HORACE H. DAYTON, of the city and county of Worcester, State of Massachusetts, have invented certain new and useful Improvements in the Construction of Corsets and Skirt-Supporters; and I do hereby declare the following to be a full, clear, and exact description of the same, due reference being had to the drawings herewith presented.

In said drawings, Figure 1 is a back view. Fig. 2 is a front view.

The same letters denote the same parts in each.

The object of my invention is to make a corset that shall be adjustable and easily fitted to the body, and that will remain so while being put on and off, and at the same time form a support for the skirts as desired, the whole supported by shoulder-straps so arranged as to prevent injurious pressure on the breast, and yet not inclined to slip off the shoulders. To these ends I construct the body A (see drawings) with the opening B down the back to be laced up to adjust it to the

wearer, and the front C with clasps, as shown, that it may be easily removed, and attaching the shoulder-straps D D near the lacing on the back and nearly around to the arm-pit in front, where they buckle to the elastics I I, and are united on the back by the elastic band H, which effectually keeps the straps from slipping off the shoulders, and in connection with them forms a shoulder-brace for the wearer, the lower part of the corset being spread, and provided with one or more extensors, as J, to support and extend the skirt similar to bustles.

I do not claim combining corsets and skirt-supporters or bustles; but

I claim—

A corset combining the adjustable shoulder-straps D, body A, and extensor J, or the equivalent thereof, substantially as shown and described.

HORACE H. DAYTON.
